UNITED STATES PATENT OFFICE

128,241

DESIGN FOR A COMBINATION DISPLAY RACK AND STOCK CABINET

Fred E. Deschauer, Lake Zurich, Ill.

Application August 7, 1940, Serial No. 94,287

Term of patent 14 years

To all whom it may concern:

Be it known that I, Fred E. Deschauer, a citizen of the United States, residing at Lake Zurich, in the county of Lake and State of Illinois, have invented a new, original, and ornamental Design for a Combination Display Rack and Stock Cabinet, of which the following is a specification, reference being had to the accompanying drawing forming part thereof.

Figure 1 is a front perspective view of a combination display rack and stock cabinet, showing my new design; and

Figure 2 is a top plan view thereof, on a reduced scale.

The side of the article not shown in the drawing is substantially the same as the side shown in Figure 1.

I claim:

The ornamental design for a combination display rack and stock cabinet, as shown and described.

FRED E. DESCHAUER.
